RELAY.

No. 813,710.

Specification of Letters Patent.

Patented Feb. 27, 1906.

Application filed July 21, 1904. Serial No. 217,581.

To all whom it may concern:

Be it known that I, HEMMING JOHANSSON, a subject of the King of Sweden and Norway, and a resident of Stockholm, Sweden, have 5 invented certain new and useful Improvements in Relays, of which the following is a specification.

My invention relates to what are known as "slow-acting" relays; and it consists of a 10 novel construction of armature and of other structural elements and combinations of parts hereinafter fully described, and particularly pointed out in the claims.

One of the objects of my invention is to 15 construct a relay the armature of which will respond to direct and pulsating currents of electricity, but which remains unresponsive to alternating currents.

Another object of the invention is to so 20 construct and mount the armature that by attaining a large leverage the exertion of a minimum amount of power will cause the application of a maximum amount of force at the contact-points.

25 A further object is to combine the several elements in such a manner that when the armature has been attracted to one of the pole-pieces of the electromagnet it will remain so without vibration, causing the contact to be 30 steady and secure, the armature being unaffected by the action of an alternating current and only receding from the pole-piece upon stoppage of the pulsating current.

In the accompanying drawings, wherein 35 like reference characters refer to like parts throughout, Figure 1 is a front elevational view of the relay. Fig. 2 is a side elevational view of the relay. Fig. 3 is a top plan view of the same, and Fig. 4 is a perspective view 40 of the armature.

Referring to the drawings, 1 designates a bridge upon which are mounted the electromagnetic coils 2 and 3. Passing through the coils are the pole-pieces 4 and 5, upon the top 45 of which the plate 6 is secured. Resting upon the plate 6 and properly fastened thereto is an insulating-block 7, carrying contacts 8 and 9, held by screws 10 passing through plates 9^x, which form part of the contacts 8 and 9 and overlap the upper edges of the block 7. A permanent magnet 11 is secured to the bridge 1 and extends therefrom to the plate 6. The pole-pieces 4 and 5 are sur-

rounded by copper sockets 12 and 13, respectively, to a height flush with the top of the 55 spools 14 and 15 of the coils of the magnet.

The armature 16 is mounted on a rod or pin 17, extending upwardly from the bridge 1. At its lower end the pin 17 has a pivot 18, which finds a bearing in the bridge 1. As 60 shown clearly in Fig. 4, the armature 16 has two hook or claw shaped parts 19, the inner or scooped-out portions 20 being adapted to rest against the pole-pieces 4 and 5. The armature may be compared to a double-armed 65 lever fulcrumed at its center 17. For the purpose of preventing the armature from adhering to the pole-pieces when the flow of the current has ceased screws 21, having stop-nuts 22, are threaded through the hooked 70 portions of each end of the armature. Projecting upwardly from the armature 16 is a pin 23, having an insulated cover 24 for the purpose of pressing the contacts 8 and 9 together when the armature is attracted to the 75 pole-piece 5.

Mounted upon the plate 6 is a standard 25, having a threaded bore through which a slotted screw 26 passes horizontally. A screw 27 extends downwardly into the standard 25 80 and reaches into the slot 28 of the screw 26. A thumb-nut 29 is threaded on the slotted screw 26 for regulating the tension at which the armature is held, as hereinafter explained. The screw 26 is provided at one 85 end with an eye 30, retaining one end of a spiral spring 31, the other end of the spring encircling the pin 32, mounted upon the armature 16.

The operation of the relay is as follows: 90 When a pulsating current flows through the electromagnet, the armature will be attracted, and the end resting against pole 4 being repulsed and the opposite end drawn against the tension of spring 31 toward and against pole 5 95 and retained there steadily throughout the flow of the current. This action of the armature will cause the pin 23 to press against spring 9 and force it into contact with spring 8. Owing to the proximity of the pin 23 to 100 the rod 17, (the fulcrum of the lever,) the pin 23 will exert considerable force against spring 9 without the need of a large expenditure of power at the end of the armature. When the current has ceased to flow through the 105 coils, the spring 31 will draw the armature

back to its normal position—viz., with one end thereof contacting with the pole 4. The tension of the armature may be regulated by more or less extending the spring 31. When 5 the spring 31 is properly adjusted, the screw 27 is screwed home into the slot 28 of the screw 26 and so held tightly. Should an alternating current pass through the electromagnetic, it would not have the effect of breaking contact between the pole 5 and the corresponding end of the armature. This is due 10 partly to the inertia of the armature itself and in part to the copper sockets surrounding the poles, which tend to offset the energizing 15 of the pole-pieces.

Having now described my invention, what I claim as new, and desire to secure by Letters Patent, is—

1. In a relay, the combination of electro- 20 magnetic coils, an insulating-block associated therewith, a contact secured at each end of said block, and an armature adapted to alternately engage the poles of the electromagnetic coils and to press the contacts together, substantially as described.

2. In a relay, the combination of electro- 30 magnetic coils, a pivoted armature, a set of contacts, and means near the center of the armature for pressing the contacts together when the armature is attracted, substantially as described.

3. In a relay, the combination of electro- 35 magnetic coils, an insulating-block arranged over the coils, a spring-contact secured to each end of said block, the free ends of said contacts overlapping, and an oscillating armature adapted to press said contacts together, substantially as described.

4. In a relay the combination of electro- 40 magnetic coils a pivoted armature having a hook-shaped part at each end thereof and a set of contacts arranged to be pressed together when the armature is attracted, said hook-shaped parts being adapted to alternately engage the pole-pieces of the coils, substantially 45 as described.

5. In a relay, the combination of electro- magnetic coils, a double-armed armature pivoted at its center, a set of contacts, and means near the center of the armature for pressing 50 the contacts together, substantially as described.

6. In a relay, the combination of electro- magnetic coils, an armature with hook-shaped ends adapted to alternately partially encircle 55 the pole-pieces of said coils, a set of contacts associated with the armature, means for returning the armature to its normal position and means for preventing the armature from adhering to said pole-pieces upon cessation of 60 the flow of current, substantially as described.

7. In a relay, the combination of electro- magnetic coils, an armature pivoted intermediately of the coils, a set of contacts adapted to be pressed together by the armature when 65 the latter is attracted, and means for regulating the tension of the armature, said means comprising a slotted screw mounted in a standard, and a spring extending from said screw to a post on the armature substantially 70 as described.

8. In a relay, the combination of electro- magnetic coils, pole-pieces passing there- 75 through, said pole pieces being surrounded by copper sockets, a plate mounted on said pole- pieces carrying an insulating-block, contacts on said block, an armature pivoted near its center having an insulated pin for pressing together said contacts, an adjustable screw mounted on said plate, a second plate, a sec- 80 ond pin on the armature and a spring extending from said screw to said second pin for re- turning the armature to its normal position, substantially as described.

In testimony whereof I have signed my 85 name to this specification in the presence of two subscribing witnesses.

HEMMING JOHANSSON.
